US0D1106145S

(12) **United States Design Patent** (10) **Patent No.:** **US D1,106,145 S**
(45) **Date of Patent:** **** Dec. 16, 2025**

(54) **MOBILE COMPUTING DEVICE**

(71) Applicant: **ZEBRA TECHNOLOGIES CORPORATION**, Lincolnshire, IL (US)

(72) Inventors: **Sunghun Lim**, Bethpage, NY (US); **Jiwei Huang**, Syosset, NY (US); **Chad Chaumont**, Mount Sinai, NY (US); **JaeHo Choi**, Whitestone, NY (US); **Carl A. Thelemann**, East Islip, NY (US); **Ricardo F. Perez**, New Haven, CT (US)

(73) Assignee: **Zebra Technologies Corporation**, Lincolnshire, IL (US)

(**) Term: **15 Years**

(21) Appl. No.: **29/809,625**

(22) Filed: **Sep. 29, 2021**

(51) **LOC (15) Cl.** **14-02**

(52) **U.S. Cl.**

USPC ..... **D14/426**; D14/138 G; D14/341

(57) **CLAIM**

The ornamental design for a mobile computing device as shown and described.

DESCRIPTION

FIG. 1 is a first perspective view of a mobile computing device;

FIG. 2 is a second perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and,

FIG. 8 is a bottom view thereof.

1 Claim, 6 Drawing Sheets
